FEEDING MECHANISM FOR SHAKER CONVEYERS

Charles A. Pratt, Chicago, Ill., assignor to Goodman Manufacturing Company, Chicago, Ill., a corporation of Illinois

Application December 1, 1941, Serial No. 421,141

2 Claims. (C.I. 198—220)

This invention relates to improvements in feeding mechanisms for shaker conveyors of the type used for picking up and transporting loose material such as coal, rock, or the like in mines.

The principal object of the invention is to provide a positive feeding means for an extensible trough section, auxiliary to the friction grip feeding mechanism, for feeding said extensible trough section where the pitch of the coal seam may be such as to impair the efficiency of the friction grip feeding mechanism.

More particularly, the present invention constitutes an improvement in the type of auxiliary ratchet feeding mechanism disclosed in the Letters Patent of Loyal F. Crawford, No. 2,251,118, issued July 29, 1941, and reissued January 20, 1942, as No. 22,008, whereby said auxiliary ratchet feeding mechanism is provided with automatic means for imparting a plurality of successive feeding strokes to the extensible trough section, when desired, so as to eliminate any necessity for manual control of the friction grip mechanism during the operation of the ratchet feeding mechanism.

The invention may best be understood by reference to the accompanying drawings in which:

Figure 1 is a view in side elevation of a shaker conveyor trough line, showing a friction grip feeding mechanism of conventional form, with an auxiliary positive feeding mechanism constructed in accordance with my invention associated therewith;

Figure 2 is a top plan view of the trough line shown in Figure 1;

Figure 3 is an enlarged view in side elevation of the trough line with the friction grip block mechanism adjusted in position to advance the extensible trough section, and showing parts of the auxiliary feeding mechanism in substantially longitudinal section;

Figure 4 is a view somewhat similar to Figure 3, but showing the parts in a different position of adjustment;

Figure 5 is an enlarged plan view of a portion of the pan line adjacent the feeding mechanism, with certain parts broken away and shown in horizontal section to illustrate certain details of construction;

Figure 6 is a section taken on line 6—6 of Figure 5;

Figure 7 is a section taken on line 7—7 of Figure 5; and

Figure 8 is an enlarged view of a portion of the trough line including a swivel and pendulum

and the method of providing fluid pressure in the system.

In the drawings, the embodiment of my invention illustrated includes a shaker conveyor trough line 10 having a swivel 11 interposed therein, to permit the forward end of the trough line to be swung from side to side and enable material to be gathered from various points along a working face. Said swivel is of an ordinary construction well known to those skilled in the art and has a conveyor trough section 12 secured to and projecting from its forward end.

The conveyor trough section 12 has a friction gripping type of feeding mechanism 15 pivotally mounted on the forward end thereof and disposed in advance thereof, which is adapted to extend or retract an extensible trough section 16 with respect to said conveyor trough section. Said extensible trough section is mounted at its rear end on a shoe 17 and has a shovel 18 projecting from the forward end and forming a continuation thereof and resting upon the ground at its forward end. Flanged bearing plates 19, 19 extend laterally from the upper sides of said extensible trough section, and are adapted to form a track for flanged rollers 20, 20 mounted in the upwardly projecting sides of a bracket 21. Said bracket extends beneath and forwardly from and upwardly along opposite sides of said conveyor trough section and forms a support for the feeding mechanism 15 and a means for supporting said conveyor trough section on said extensible trough section.

The feeding mechanism 15 herein shown is of conventional form previously employed in devices of this character, so will only herein be described in so far as is necessary to make my present invention clearly understandable. Said feeding mechanism includes a pair of spaced carrier members 22, 22 each having a pair of friction grip blocks 23 and 24 which are adapted to selectively engage the upper and lower surfaces of the bearing plates 19, 19. Said carrier members each have pivotal connection at their lower end with a spring link 25 which forms a means for engaging said grip blocks with said bearing plates. Said spring links are disposed below the trough section 16 and are yieldably mounted in a forked bracket 26, which projects forwardly from and is pivotally mounted on the forward end of the bracket 21. A link 29 is pivotally connected to the upper end of each of said carrier members on a bolt 30, which bolt also forms a means for pivotally connecting the upper grip block 24 to said carrier member. Said link ex-

tends downwardly and rearwardly from said carrier member and is pivotally connected at its rear end to a crank 31 (see Figure 3).

A pair of hand levers 33, 33 is provided to adjust the position of the carrier members 22, 22 to extend the shovel 18 and extensible trough section 16, which, as herein shown, is in a rearwardly inclined position, or to a forwardly inclined position to retract said shovel and extensible trough section. Said hand levers are mounted on opposite ends of a transverse shaft 34 which is mounted adjacent its ends in the brackets 26, 26. Said hand levers are operatively connected with the carrier members 22, 22 to change the inclination thereof, by means of cranks 35, 35, mounted on the shaft 34 between the sides of the brackets 26, 26, and links 32, 32 connecting said cranks with the cranks 31, 31 (see Figure 3).

A fluid pressure cylinder 36 is pivotally mounted at its rear end on a bracket 37 beneath the trough section 12 by means of a transverse pin 38. Said cylinder is provided with a piston 40 having a piston rod 43 extending forwardly therefrom. Said piston rod has a pawl 44 pivotally mounted on the forward end thereof on a pin 45 secured at its ends in a forked bracket 46 which is secured to the forward end of said piston rod. A compression spring 47 is provided to yieldingly hold said pawl in engagement with a rack 48 mounted on and extending along the underside of the extensible trough section 16. The structure previously described is similar to that disclosed in previously mentioned Reissue Patent No. 22,008.

Referring now more particularly to the novel features of my invention, I provide a second pawl 55 pivotally mounted between the side walls 56, 56 of an arm 57 adjacent the rear end of the latter, by pin 58. The arm 57 is pivotally connected at its front end to the pivot pin 38 on bracket 37. A compression spring 59 is provided to yieldingly hold the pawl 55 in engaging position relative to the rack 48.

The cylinder 36 and arm 57 are simultaneously raised or lowered about the axis of pin 38 to permit their respective pawls 44 and 55 to be moved into or out of engaging position relative to the rack 48. In the form shown, this adjustment is afforded by either one of the hand levers 33 through a pair of links 49, 49 pivotally connected to said hand levers at their forward ends and each having pivotal connection with similar rocking levers 50 and 60 at opposite sides of the trough line, as shown in Figure 5.

The rocking levers 50, 50 are secured to the outer ends of a pair of transverse, coaxial shafts 51, 51, respectively, mounted on the underside of the conveyer trough section 12 in spaced apart brackets 52, 52 depending from the bracket 21 (see Figure 6). Said shafts each have an eccentric disc or cam 53 on the inner end thereof adapted to have engagement with projections 54 projecting laterally in opposite directions from the forward end of the cylinder 36.

Similarly, the rocking levers 60, 60 are secured to the outer ends of a pair of shafts 61, 61, respectively, mounted in spaced-apart brackets 62, 62 depending from the trough section 12, and each having an eccentric 63 on the inner end thereof adapted to have engagement with projections 64 projecting laterally in opposite directions from the rear end of arm 57, as shown in Figure 7.

The cams 53, 53 controlling the position of

pawl 44, and cams 63, 63 controlling the position of pawl 55, are so shaped that when the hand levers 33, 33 are positioned to extend the extensible trough section 16 with respect to the conveyer trough 12, as shown in Figure 3, they will raise both of said pawls into engaging position relative to the rack 48, as shown in Figure 3. When the hand levers are positioned to retract said extensible trough section, said cams 10 permit the pawls to drop out of engaging position relative to the rack 48, as shown in Figure 4.

Fluid under pressure may be applied to the cylinder 36 and piston 40 in any suitable manner; as herein shown, an air pump 70 with a storage tank 71 being mounted on a base 72 anchored by mine jacks 73, 73 and the pump being operated by means of a pendulum 74 which is reciprocated by the shaking movement of the trough line 10 in the usual manner. Details of the fluid supply and control means need not be described in detail, as they form no part of the invention, excepting to point out a manual control valve 75 with valve handles 76 for supplying air through pipes 77, 78 leading to opposite ends of the cylinder 36.

With the construction and arrangement above described, it will be understood that when the conveyer is operated along an ascending grade of such a pitch that the friction grip blocks 23, 23 and 24, 24 will not efficiently extend the extensible trough section 16, manipulation of the valve handle 76 will cause the piston 40 and pawl 44 engaging the rack 48, to positively extend said extensible trough section, through a stroke equal to the permissible movement of the piston 40 in cylinder 36. During this extending movement, the teeth of rack 48 will move forwardly relative to the pawl 55 with the usual ratcheting action. After the piston 43 has been moved to the limit of its forward stroke, however, the pawl 55 will hold the extensible trough section 16 positively against retractive movement while the piston 40 and its pawl 44 are returned to its initial rearward position. In this manner said piston and pawl are enabled to make as many repeated thrusting strokes as may be required to advance the extensible trough section.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a shaker conveyer, a conveyer trough section, an extensible trough section, friction feeding means actuated by movement of the conveyer for extending said extensible trough section, and one of said trough sections carrying a power-operated extensible thrusting member thereon having one-way ratchet feeding engagement relative to the other of said trough sections for positively extending said extensible trough sections through a predetermined forward stroke, and other one-way ratchet means between said trough sections for automatically holding said extensible trough section against retraction while said thrusting member is being retracted for a repeated forward stroke, and common control means for rendering both of said ratchet means ineffective at will to permit retraction of said extensible trough section.

2. In a shaker conveyer, a conveyer trough section, an extensible trough section, feeding means for extending said extensible trough section from or retracting said extensible trough section within said conveyer trough section, control means for positioning said feeding means to extend or retract said extensible trough section, other means independent of said feeding means for positively extending said extensible trough section including a power-operated extensible thrusting member on one of said trough sections having one-way ratchet feeding engage-

ment relative to the other of said trough sections, and a second ratchet device forming an automatic holding connection between said trough sections while said thrusting member is being retracted for a repeated forward stroke, and means operatively connected with said control means for simultaneously rendering both of said ratchet devices ineffective when said control means is in position to cause said feeding means to retract said extensible trough section.

CHARLES A. PRATT.
